R. BLACK

PROCESS AND APPARATUS FOR DISPENSING LIQUIDS

Filed June 10. 1922

UNITED STATES PATENT OFFICE.

ROE BLACK, OF GEM, NEBRASKA.

PROCESS AND APPARATUS FOR DISPENSING LIQUIDS.

Application filed June 10, 1922. Serial No. 567,284.

To all whom it may concern:

Be it known that I, ROE BLACK, a citizen of the United States, residing at Gem, in the county of Logan and State of Nebraska, have invented certain new and useful Improvements in Processes and Apparatus for Dispensing Liquids, of which the following is a specification.

The invention relates to a liquid dispensing device and has as an object the provision of a device which may be used for placing oil in the crank case of automobiles, or other like service. A further object of the invention is the provision of a device which shall utilize the force of compressed air to cause the liquid to rapidly escape from the outlet of the container.

An illustrative embodiment of the invention is shown in the accompanying drawings, in which—

Fig. 1 is a diagrammatic side elevation of an oil tank equipped with the delivery device for attaching the can for reception of oil;

Fig. 2 is a detail vertical section parallel with the view of Fig. 1 showing the attaching means;

Fig. 3 is a central vertical section of a form of dispensing container;

Fig. 4 is a perspective view of a valve shown in Fig. 2;

Fig. 5 is a detail section on an enlarged scale of a portion of the device shown in Fig. 3;

Fig. 6 is a central vertical section of a cap.

The device is especially adapted for use with the usual form of oil tank 10 found in automobile service stations which are usually provided with a measuring pump built there-

in. The container 11 shown in Fig. 3 is adapted to be attached to the outlet 14 of the pump, not shown, which pump may be operated by means of a crank 12 acting through a rack and pinion device 13. When

the container 11 is attached to the outlet 14 and the pressure of the pump is exerted upon the oil to cause the same to be forcibly discharged into the container, air in the outlet pipe 14, as well as the air already in

the container 11 will be compressed by the pressure of the pump to a fraction of its original volume, being trapped over the oil flowing into container 11 when the container is applied in an inverted position as is preferred.

To readily attach the container to the out-

let pipe 14, means which are readily separable are provided upon the nozzle of the container and co-acting means upon the end of the outlet pipe. As shown in the illustrated embodiment of the invention the nozzle 15 of the container is provided with a pair of studs 16 which are adapted to enter grooves 17 formed upon each side of an opening 18 in a cap 19 secured to the outlet pipe. The end of the nozzle 15 when placed in connection with the cap 19 contacts with a gasket 20, which may be of leather, or other suitable material, to make a tight joint. With the studs 16 entered within the cap 19 the container 11 is given a partial rotation when the studs 16 contact with cam surfaces 21 to cause the nozzle to press tightly against the gasket 20. When securely attached in this manner and the pump is operated the oil will be forced into the container with compression of the air therein as already described.

To automatically close the nozzle 15 of the container a spring pressed valve is provided within the container, which valve is adapted to be forced open by the pressure of the oil flowing in. In the form of the invention chosen for illustration the valve is shown in the form of a tapered plug 22 fitting within the tapered inner portion of the nozzle 15. To hold the valve to its seat a spring 23 is shown acting in compression against a washer 24 held in position by a pin 25. Spring 23 need not be of great strength since the internal pressure within the container will tend to hold the valve closed. A form of assembly for the valve 22 with the container is shown comprising plug 26 screwing into the bottom 27 of the container and being of such a diameter that the valve 22 may pass through the opening into which the plug screws. For ready control of the valve when it is desired to allow the oil to escape the valve rod 28 is passed through a stuffing box plug 29 pressing upon the gland 30 in the plug 26, passing through the plug and terminating in a handle 31. Preferably the bottom 27 of the container is made concave with a depth of depression sufficient to house the handle 31 and allow the can to sit upon its margin 32 securely when not in use. A ready means of retraction of the valve 22 is provided in the form of a cam washer 33 which is immovably secured to the plug 26. The washer 33 is formed with a depressed portion pass-

ing diametrically through its center and with raised portions 34 upon each side thereof, so that when the handle 31 is revolved through an angle of 90° the portions of the handle in contact with the washer will ride up upon the cam surfaces with compression of the spring 23 and retraction of the valve 22 sufficient to allow the compressed air in the container to eject the oil. The spring 23 is shown seating upon the stuffing box plug 29 and therefore tending to keep the stuffing box tightened.

After the container 11 has been filled by the pump it is desirable to have the oil in the attaching connection 19 and in a portion of the outlet pipe 14 returned to the tank so that these portions of the outlet may be filled with air to be compressed within the container upon subsequent filling. A form 20 of valve to provide this action is shown in Figs. 3 and 4, in which a washer 35 is shown carrying a yoke 36 adapted to extend within the bore of the portion 37 of the connection which screws upon the outlet pipe 14. In 25 alignment with the threaded terminal portion 38 of the outlet pipe 14 there is shown a return pipe 39 extending into the tank 10. A valve 40 in coaction with a seat 41 is provided to control the return pipe 39. The 30 valve 40 is shown as suspended from the yoke 36 by means of its rod 42, through a spring 43 acting in tension, so that when the washer 35 is depressed by the pressure of the nozzle 15 upon the gasket 20, which 35 is superposed upon the washer 35, depression of the yoke 36 will stretch the spring 43, resiliently pressing the valve 40 upon its seat. To raise the valve 40 from its seat to allow the oil to return to the tank, a 40 spring 44 is shown housed in an annular groove 45 in the connection 36', which spring holds the parts in the position shown in Fig. 2 when the container 11 is absent. The pump delivering oil from the tank 10 must be so adjusted as to deliver the proper 45 quantity of oil to the container 11, making allowance, if necessary, for the oil which flows back each time through the valve 40.

The container of Fig. 11 is adapted to be 50 supplied with oil under pressure at any service station and to be carried in the car of the user with the pressure stored within it for use of the oil at a future time. To prevent accidental opening of the valve 22 55 by coming into contact with external objects the cap 46, shown in Fig. 6, is provided which cap is formed with the grooves 17' to connect with the studs 16 and the gasket 20' to provide a tight joint with the nozzle 15.

By the use of the device provided by the present invention oil may be placed in the crank case of an automobile without the use of a funnel and without danger of spill-

ing the same upon the surrounding portions 65 of the motor. The invention is also useful in any other location in which it is desired to supply a quantity of liquid quickly and accurately under perfect control. Minor 70 changes may be made in the physical embodiment of the invention without departing from its spirit.

What I claim is:

1. In a liquid dispensing device, in combination, a container comprising a nozzle 75 having an internal valve seat, a plug in the bottom of said container, a rod extending through said plug, a valve carried by said rod coacting with said seat, the opening 80 receiving said plug being larger than said valve whereby the assembly of the valve and plug may be removed as a unit from the container.

2. In a liquid dispensing device, in combination, a container having a depressed bottom and a nozzle, an internal valve seat for said nozzle, a plug in said bottom, a valve rod passing through said plug, a valve carried by said rod coacting with said seat, a spring connected to said rod and operating against said plug to hold the valve upon 90 its seat, a handle upon said rod exterior of said plug wholly housed in said depression whereby said container may sit upright 95 upon the margin of its bottom.

3. In a liquid dispensing device, in combination, a container having a nozzle, an internal valve seat for said nozzle, a plug in the bottom of said container, a valve rod passing through said plug, a valve carried 100 by said rod coacting with said seat, a handle upon said rod exterior of said bottom, a cam upon said plug coacting with said handle for retraction of said valve when the handle is rotated, spring means to normally 105 hold the valve upon its seat.

4. The process of charging a liquid dispensing device which comprises introducing liquid thereinto by upward flow with compression of trapped air in the container. 110

5. The process of charging a liquid dispensing device which comprises providing a container with an inwardly opening valve, attaching said container to a supply of liquid under pressure in a position to trap 115 air in said container, introducing liquid into said container under pressure with compression of trapped air therein.

6. The process of charging a liquid dispensing device which comprises providing 120 a container with an inwardly opening valve, attaching said container in an inverted position to a source of supply of liquid under pressure, causing said liquid to open said valve and flow into said container with compression of trapped air therein.

ROE BLACK,
